UNITED STATES PATENT OFFICE.

WILLIAM C. HOMAN, OF MERIDEN, CONNECTICUT, ASSIGNOR TO LEWIS T. WILCOX,
OF PEEKSKILL, NEW YORK.

STOVE.

Application filed October 1, 1927. Serial No. 223,299.

My invention has particular reference to oil stoves of the type in which wick burners are supplied by a pipe leading from a reservoir or tank which is commonly mounted on 5 one end of the stove. The burners are ordinarily mounted on a base which is usually a flat sheet metal member, and the supply pipe is located along the top of this burner base and coupled to the individual burners of 10 which there may be one or a number, the seats for the burners being often carried by the pipe itself.

One of the features of my invention is the fact that the supply pipe is underneath the 15 burner base. This is desirable not only for appearance but also because the burner base can be more easily cleaned. The burner seats are, according to my invention, formed in the burner base itself, and the connection of the 20 burners with the supply pipe may with such an arrangement be disposed above the burner base for easy manipulation. My invention also contemplates a connection which may be tightened up after the burner is in place without placing any strain upon the elbow or 25 other part attached to and leading from the burner.

Another feature of my invention is the attachment of the fuel tank or reservoir which 30 enables it to be easily removed, a matter of importance in shipping, and also permits of ready cleaning of the supply pipe. The mounting for the tank is of a character which supports it rigidly from the side or end of 35 the stove, but in spaced relation thereto, thereby minimizing the transfer of heat to the fuel in the tank.

Other novel features of construction will 40 appear from a detailed description of one embodiment of my invention shown in the drawings by way of illustration.

Fig. 1 is a front elevation partly in section of a stove constructed in accordance with my invention;

Fig. 2 is a section of the same taken on line 45 2-2 of Fig. 1 with the burners removed to better illustrate the burner base;

Fig. 3 is a sectional detail of one burner and the portion of the burner base associated 50 therewith;

Fig. 4 is another sectional detail of the same;

Fig. 5 is a section on line 5-5 of Fig. 3, and

Fig. 6 is a sectional detail showing the man-

ner of connecting the fuel supply line to the supply tank.

In the illustrated embodiment of my invention I have shown a two-burner oil stove of suitable dimensions that each burner may 60 be utilized to heat two cooking holes (not shown) if so desired. The stove is supported upon four legs 1 to which is secured the stove top 2, burner base 3 and end or side walls 4, all of which parts may conveniently 65 and economically be stamped from sheet metal and securely bolted or otherwise attached together to form a rigid stove frame assembly. A pair of burners 6 and 7 are mounted upon the burner base 3 which is struck up at suitable locations to provide raised annular bosses constituting raised seats upon and over which the burners fit. Each boss is struck up from the base to provide an 70 upwardly extending flange 8, the outer diameter of which is equal to the outer diameter of the burner shell, which flange is turned inwardly and slightly downwardly to form a downwardly inclined seating ledge 9 of a 75 width equal to the thickness of the double 80 wall of the lower end of the burner or burner shell. The metal is then turned upwardly again to provide a circular retaining wall 10 adapted to extend into the shell when the 85 burner is placed thereon, after which the metal is flanged inwardly to form an annular flange 11 the center being left entirely open.

Fuel is fed to the burners through a feed pipe 12 leading from the fuel tank supported upon the end or side of the stove. This fuel 90 pipe runs underneath the burner base 3 and is supported immediately adjacent the under surface by stirrups or straps 13 which are secured to the burner base. Communication is provided between the supply pipe 12 and 95 each of the burners by a coupling which is disposed above the burner base and is thereby readily accessible for manipulation and also one which provides packed joints without subjecting the burner nipple or elbow 100 itself to any strain. As shown this coupling consists of a packing nipple or bushing 14 which passes through an opening provided for the purpose in the burner base and is threaded into the supply pipe, a packing nut 105 15 which provides a quickly releasable slip joint for the straight nipple or short pipe length 16, and an elbow 17 which is riveted or otherwise secured to the burner shell and has the upper end of the nipple 16 threaded 110

into it. The packing nut 15 is tightened after the burner is on its seat without placing any longitudinal strain upon the nipple 16 and its connected parts.

5 One end of the supply pipe 12 is capped in the usual manner and the other end is connected to the fuel tank. As illustrated, my invention contemplates a separable connection between the end of the supply pipe 12 10 and the bent tube 18 which leads to the sub-tank 19 of the oil reservoir. This separable connection is also a packed joint similar to that employed in the connections between the burners and the supply pipe, consisting 15 of the packing bushing or nipple 14' which is threaded into the end of the supply pipe, and the packing nut 15'. This enables the supply tube 12 to be readily cleaned, the removal of the cap on the one end and of the 20 pipe 18 on the other end leaving the supply pipe entirely open for the purpose.

My invention contemplates readily releasable means for securing the burner to the seat, by hooking or latching it to the supply pipe 12. In the form shown, these means 25 are a wire hook or latch 20 which is bent in approximation to a V shape and is attached at its upper end to the usual spreader bar 21 which extends across the inside of the burner. 30 This attachment may be in any suitable manner, as by looping the ends through holes provided for the purpose near the ends of the spreader bar. The hook member 20 thus hangs freely through the opening in the 35 burner seat and has its bottom end bent in the form of a hook and is of proper length to hook underneath the supply pipe 12. While the attachment of the burner to the burner base may thus be quickly and easily effected, 40 and while it may be as easily and quickly released, yet it is by these means very securely held on its seat.

The fuel tank or reservoir consists of the 45 subtank 19 and the main tank 22 which is inverted over the subtank in the usual manner and is provided with a gauge 23. The tank and subtank are supported upon one end wall 4 and spaced therefrom by a sheet metal bracket 24 which is substantially U 50 shape in formation, having the ends of its arms flanged outwardly and secured to the side wall 4. The lower portion 25 of the bracket wall is secured to the subtank 19 in any suitable way as by soldering, while the 55 upper portion 26 curves inwardly to the shape of the side wall of the main tank and bears against it and constitutes a rest therefor. The bracket 24 thus provides a rigid support for the subtank and a solid rest for the main 60 tank, and holds both in spaced relation from the wall 4, thereby permitting an insulating layer of air to pass between the wall 4 and the tank.

If it is desired to remove a burner for 65 cleaning or to renew a wick it is only neces-

sary to unscrew the packing nut 15 a little to release the packing pressure upon the nipple 16, release the hook 20 and raise the burner a sufficient distance to clear the retaining wall 10, after which it may be completely removed. In replacing the burner the preceding steps are reversed and the burner is securely and rigidly held upon the base. The hooks 20 prevent the burner from being raised and also restrain any rotative movement of the burner. The packing nuts 15 are set up after the burner is placed on its seat without subjecting the elbow 17 to any pull or strain. For shipment, as well as other purposes, the fuel reservoir may be readily removed by releasing the bracket 24 from the side wall of the stove and by letting up on the packing nut 15' sufficiently to release the pipe 18, and the fuel tank may be separately crated and the cubical size of the crate for the stove be thereby materially reduced.

Under some conditions of use the stove is set up without the legs. In such case the burner base sits upon the floor, and in order to provide for the admission of air to the burners, I form air inlet holes 27 in the side flanges of the base, these holes being properly proportioned for the purpose.

It is obvious that various changes may be made in the illustrated embodiment of my invention without departing from the spirit or scope thereof as defined in the appended claims.

I claim:

1. In a stove, a sheet metal burner base 10 having a burner seat struck up therefrom, a burner on said seat, a fuel supply pipe coupled to said burner and means for detachably securing said burner upon said seat.

2. In a stove, a sheet metal burner base 105 having a burner seat struck up therefrom, a burner on said seat, a fuel supply pipe disposed underneath the base, a coupling between the burner and supply pipe extending through the base and means for detachably retaining said burner upon said seat.

3. In a stove, a burner base having an open burner seat thereon, a fuel supply pipe supported underneath the base and extending across the open seat, a burner on the seat, a coupling between the burner and supply pipe extending through the base and means for securing said burner to said seat.

4. In a stove, a burner base having an open burner seat thereon, a fuel supply pipe supported underneath the base and extending across the open seat, a burner on the seat, and means for latching the burner to the supply pipe.

5. In a stove, a burner base having an open burner seat thereon, a fuel supply pipe supported underneath the base and extending across the open seat, a burner on the seat, and a resilient hook member depending from the inside of the burner through the open 125

burner seat and adapted to be releasably hooked underneath the supply pipe.

6. In a stove, a burner base having an open burner seat thereon, a fuel supply pipe supported underneath the base and extending across the open seat, a burner on the seat, a transverse spreader bar secured to the inside of the burner, and a wire hook member suspended therefrom and adapted to be releasably hooked underneath the supply pipe.

7. In a liquid fuel stove, a sheet metal burner base having an open burner seat struck up therefrom, a fuel supply pipe supported underneath the base and extending

across the open seat, a burner on the seat releasably hooked to the supply pipe, a telescopic packed coupling between the supply pipe and burner, a U-shape sheet metal bracket having the free ends of its legs removably secured to a side wall of the stove, a fuel tank attached to the bracket and supported thereby in spaced relation to the stove wall, and a coupling pipe leading from the fuel tank to the supply pipe and detachably coupled to the latter.

In witness whereof, I hereunto subscribe my signature.

WILLIAM C. HOMAN.
